LINK FOR AN IDENTIFICATION BRACELET OR SIMILAR ARTICLE

Uno L. Tienson, San Francisco, Calif.

Application November 23, 1949, Serial No. 6,228

Term of patent 7 years

(Cl. D45—4)

To all whom it may concern:

Be it known that I, Uno L. Tienson, a citizen of the United States of America, residing at San Francisco, in the county of San Francisco and State of California, have invented a new, original, and ornamental Design for a Link for an Identification Bracelet or Similar Article, of which the following is a specification, reference being made to the accompanying drawing, forming a part thereof:

Fig. 1 is a top plan view of a link for an identification bracelet or similar article showing my new design, the back of the link being plain.

Fig. 2 is an edge elevation thereof.

I claim:

The ornamental design for a link for an identification bracelet or similar article, substantially as shown.

UNO L. TIENSON.
